UNITED STATES PATENT OFFICE.

STEPHEN F. WILLIAMS, OF DEPEW, NEW YORK.

RESILIENT WHEEL.

1,198,302.

Specification of Letters Patent. Patented Sept. 12, 1916.

Application filed October 16, 1915. Serial No. 56,178.

To all whom it may concern:

Be it known that I, STEPHEN F. WILLIAMS, a citizen of the United States, residing at Depew, in the county of Erie and State of New York, have invented new and useful Improvements in Resilient Wheels, of which the following is a specification.

This invention relates to a spring or resilient wheel for automobiles and the like, which has loop-shaped flat spring spokes connecting the hub and rim.

The object of this invention is to provide a resilient vehicle wheel that cannot be disarranged in use, which is simple in construction and easy to assemble, which may be produced at low cost, and which is adapted to use solid or hard tires in such manner as to positively secure the same against circumferential slipping.

In the accompanying drawings: Figure 1 is an elevation of the wheel with parts thereof removed. Fig. 2 is a longitudinal section taken on line 2—2, Fig. 1. Fig. 3 is a fragmentary circumferential section taken on line 3—3, Fig. 2. Fig. 4 is a fragmentary longitudinal section, taken on line 4—4, Fig. 1.

Similar characters of reference indicate corresponding parts throughout the several views.

1 represents the hub of the spring wheel adapted to slip over the end of the vehicle axle and be secured thereto in any suitable manner, the same, as shown, being provided with a conical bore 2 and a keyway 3. The rear end of this hub is provided with an integral annular flange 4 provided with a circular row of bolt holes 5 which pass longitudinally through said flange adjacent to its periphery. In front of said flange and integral with the hub is formed an annular abutment 6 which is provided on its periphery with a circumferential row of longitudinal locking grooves or notches 7. Arranged radially around this annular abutment are a plurality of horseshoe-shaped flat spring spokes each spoke comprising two legs 8 connected at their outer ends by a curved bow 80 and each leg having its inner end provided with a foot 9 that lies circumferentially along the periphery of the abutment. The feet of the legs of each spring project toward each other and are provided at their opposing ends with inwardly projecting toes 90 which engage with one of the grooves 7 in the

abutment. A cup-shaped hub cap has its disk 11 provided with a longitudinal bore 12 whereby the same is slipped over the outer end of the hub and the same is also provided with a circular row of holes 13 and also with a rearwardly projecting annular flange 14 which is provided at intervals with notches 30 so as to divide this flange into a plurality of sections. Each leg of one spring spoke bears against a leg of an adjacent spoke and each pair of companion legs of two adjacent spokes are arranged in one of the notches 30 between two cap flange sections, as shown in Figs. 1 and 4.

40 represents a plurality of segment-shaped retaining blocks arranged in an annular row concentrically around the hub and engaging its front and rear sides with the inner sides of the hub flange and cap disk while its outer and inner sides bear respectively against the outer side of the feet of a spring spoke and the innerside of the cap flange, and the opposite ends of the block engage with the inner parts of the opposing inner sides of the companion legs of a spring spoke.

The bodies of a number of bolts 10 are passed through the longitudinal bolt holes 5 of the hub flange, through openings in the blocks 40 and through the openings of the cap disk, the heads and nuts of these bolts bearing against the outer sides of the hub flange and cap disk and operating to hold these parts together. When thus assembled the spring spokes are prevented from sliding circumferentially on the annular abutment by the toes of the spring spokes engaging with the walls or shoulders on opposite sides of the longitudinal grooves 7. Furthermore, the toes on the spokes and the recesses in the abutment which receive them facilitate the assemblage of the parts and thereby reduce the cost of production.

The felly or rim of the wheel preferably comprises a rear body ring or section 16, and a front retaining ring 17 normally arranged concentrically relatively to the hub, said body ring being comparatively wide and provided on its front side with a rabbet 18 and the front retaining ring or section 17 being narrower and seated in said rabbet of the body ring, these two felly sections being preferably detachably connected with each other by a plurality of longitudinal

bolts 19, 20 passing horizontally through the inner parts of these felly rings, as shown in Figs. 1 and 2.

On its front face or inner edge the body ring 16 is provided with a number of parallel sided spoke receiving grooves 21 each of which is curved and opens throughout its length at the inner or front side of the body ring and opens at its opposite ends at the bore of said ring. The outer wall of each spoke groove is provided with a centering recess 22 and its inner wall with a locking recess 23 both of which recesses are preferably curved and formed concentrically so that they may be cut by the same tool.

24 represents a plurality of outer spoke retaining blocks of crescent-shape one of which is arranged in each of the spoke grooves of the felly and engages its inner curved side with the inner curved wall of the respective groove, thereby producing a space between the outer curved outer side of said block and the outer wall of said groove which tapers from its opposite ends toward the central part thereof. This block is held against circumferential displacement in the space groove by means of a locking lug or key 25, preferably formed integrally on the inner side of said block and having a curved face which engages with the correspondingly shaped locking notch or recess 23 formed on the central part of the inner wall of said spoke groove, as shown in Fig. 1. The several outer spoke retaining blocks are further held in place by passing the bolts 19 through the same, as shown in Figs. 1 and 2. Those parts of the body rings of the felly between the spoke receiving grooves are preferably hollowed out, as shown at 52, for the sake of lightness and the other bolts 20 of the felly preferably pass through these spaces, as shown in Figs. 1 and 2.

On its outer side each outer retaining block is provided with a centering lug or projection 26 which is arranged opposite the centering recess 22 in the respective spoke groove, the outer side of said centering lug being curved concentrically with said recess and forming therewith an off-set seat in the central part in the respective spoke groove. On the crown of the bow of each spring spoke the same is provided with an outwardly off-set centering loop 62, preferably of curved form. In the assembled position of the parts the centering loop 62 of each spoke fits tightly in one of the off-set seats formed between a centering recess 22 and a lug 26 while those parts of the bow of each spoke on opposite sides of its centering loop are free to play radially in the tapering end parts of the spoke groove as the spoke is bent more or less under the load on the wheel when in use. By this means a reliable connection is obtained between the

spokes and the felly which effectively prevents circumferential displacement of the felly relatively to the spokes without interfering with the free action of the latter, and also enabling the parts to be machined and fitted properly at comparatively low cost.

On the periphery of the felly is preferably mounted a tire 27 preferably of solid rubber, although the same may be of any other suitable type, if desired. The preferred means for securing this tire to the felly which are shown in the drawings comprise two hook-shaped clencher flanges 28, 29 of annular form arranged on the outer edges of the front and rear felly rings, respectively, and engaging over annular beads 70 arranged on opposite sides of the base portion of the tire, as shown in Figs. 1 and 2. So that the tire may be prevented from sliding circumferentially in the rim, an anchoring strip 31, preferably of metal is cemented or otherwise secured to the base of the tire, which strip is provided on its inner side with a number of anchoring or locking lugs 32 adapted to engage a number of anchoring or locking notches 33 formed in the inner edge of the felly ring 16 in such manner that the strip with its tire may be slid rearwardly onto the felly ring 16 and interlocked therewith. On the non-traction wheels of the vehicle this anchoring means for the tire may be omitted but it is of value where power is to be transmitted. It will be noted that the arrangement of the spokes is such that they stand up under the powerful torque action incident upon suddenly starting the vehicle and the entire construction is durable and readily demountable should either the tire become worn or any replacement of parts become necessary.

I claim as my invention:

1. A resilient wheel comprising a hub, a plurality of horseshoe-shaped spring spokes having their legs at their inner ends secured to said hub and each provided on the bow at its outer end with a radially projecting off-set, and a rim provided with a plurality of seats each of which engages with the inner and outer sides of the off-set of one of said spokes.

2. A resilient wheel comprising a rim having a plurality of seats, a hub having an annular abutment which is provided with a plurality of recesses, a plurality of horseshoe-shaped spring spokes secured with their bows to said seats and the legs of each spoke having feet projecting toward each other and resting with their inner sides on said abutment and provided with inwardly projecting toes engaging with one of said recesses, and retaining blocks secured to the hub and each bearing against the outer side of the feet and the inner side of the legs of one of said spokes.

3. A resilient wheel comprising a rim having a plurality of seats, a hub having an annular abutment which is provided with a plurality of recesses, a plurality of horse-shoe-shaped spring spokes secured with their bows to said seats and the legs of each spoke having feet projecting toward each other and resting with their inner sides on said abutment and provided with inwardly projecting toes engaging with one of said recesses, retaining blocks secured to the hub and each bearing against the outer side of the feet and the inner side of the legs of one of said spokes, an annular flange arranged 10 on said hub on one side of said blocks, a cap arranged on the hub on the other side of said blocks and provided with a flange engaging with the outer side of said blocks and having slots which receive said spoke legs, 15 and bolts connecting blocks, cap and hub flange.
4. A resilient wheel comprising a hub, a rim having a plurality of curved spoke grooves each of which tapers from its ends 20 inwardly and is provided centrally with an off-set seat, and a plurality of horse-shoe-shaped spring spokes each of which is secured with its legs to said hub while its bow is arranged in said spoke groove and is provided with an off-set loop which engages 25 with said off-set seat on the rim.
5. A resilient wheel comprising a hub, a rim provided with a plurality of curved spoke grooves each of which is provided on 30 its outer wall with a centering recess, a plurality of curved retaining blocks each engaging with the inner wall of one of said grooves and provided on its outer side with a centering lug opposite the corresponding 35 centering recess and forming an off-set centering seat therewith, and a plurality of horse-shoe-shaped spring spokes each of which has its legs secured to said hub while 40 its bow is arranged in one of said spoke grooves and has an off-set loop which is arranged in said centering seat. 45
6. A resilient wheel comprising a hub, a rim provided with a plurality of curved spoke grooves each of which is provided on its outer wall with a centering recess and on 50 its inner wall with a locking recess; a plurality of curved retaining blocks each arranged in one of said spoke grooves and engaging its inner side with the inner wall of said groove and provided on its inner side 55 with a locking key which engages with said locking recess while its outer side is provided with a centering lug arranged opposite said centering recess and forming therewith an off-set centering seat, and a plurality of 60 horse-shoe-shaped spring spokes each secured with its legs to said hub while its bow is arranged in one of said spoke grooves and is provided with an off-set centering loop which engages with said centering seat. 65
7. A resilient wheel comprising a hub, a rim provided with a plurality of curved spoke grooves each of which is provided on its outer wall with a centering recess and on 70 its inner wall with a locking recess, a plurality of curved retaining blocks each arranged in one of said spoke grooves and engaging its inner side with the inner wall of said groove and provided on its inner side 75 with a locking key which engages with said locking recess while its outer side is provided with a centering lug arranged opposite said centering recess and forming therewith an off-set centering seat, a plurality of horse-shoe-shaped spring spokes each secured with 80 its legs to said hub while its bow is arranged in one of said spoke grooves and is provided with an off-set centering loop which engages with said centering seat, and bolts securing said retaining blocks to said rim. 85
